FORCE CUP

William B. Stephenson, Chicago, Ill., assignor of
one-half to George J. Irsch, Harvey, Ill.

Application January 6, 1933, Serial No. 650,377

9 Claims. (Cl. 4—255)

The present invention relates to improvements in force cups adapted for cleaning obstructed pipes.

One force cup in common use consists of an elastic cup body having a peripheral rim adapted to establish an air tight seal about the inlet of the pipe to be cleaned, and of a handle for collapsing the cup body to force the trapped air therein under pressure into the pipe. In use, the cup body is collapsed repeatedly for the purpose of dislodging by pressure impulses the sludge or other material forming the obstruction. However, due to the seal at the peripheral rim difficulties are encountered in releasing the cup body after each collapse without undoing the work that has been accomplished. Thus, actuation of the force cup frequently results in drawing some of the sludge backwardly out of the pipe, or merely in moving the obstruction to and fro without causing same to be fully dislodged.

The primary object of the present invention resides in the provision of a new and improved force cup which avoids the foregoing objections and which more specifically comprises novel means for venting the cup automatically to the exterior after each collapse so that the cup body can be expanded preparatory to the next collapse without creating in the pipe a suction force following the pressure impulse.

Other objects and advantages will become apparent as the description proceeds.

In the accompanying drawing, Figure 1 is a fragmentary vertical sectional view of a force cup embodying the features of my invention.

Fig. 2 is a fragmentary vertical sectional view showing the vent in closed position.

Fig. 3 is a transverse sectional view taken along line 3—3 of Fig. 1.

Fig. 4 is a fragmentary vertical sectional view of a modified form of the invention.

Fig. 5 is a transverse sectional view taken along line 5—5 of Fig. 4.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawing, the force cup constituting the preferred embodiment of the invention comprises a cup body 6 which is

made of elastic material, such for example as rubber, and which may be provided in any suitable form. Preferably, the cup body 6 is concave downwardly and has a peripheral rim 7 at the bottom margin adapted to establish an air tight seal about the inlet of the pipe to be cleaned. The top of the cup body 6 has a central upright integral shank 8 which is formed in its upper end with a screw threaded socket 9 separated from the interior of the cup body by an intermediate base wall 10. A suitable substantially solid handle 11 for actuating the cup body 6 is threaded at its lower end into the socket 9.

The primary feature of the invention resides in the provision of an air vent having a novel sensitive and responsive valve which will close automatically to trap the air within the cup body 6 while the same is being collapsed, and which will open to admit air to the interior of the cup body upon releasing the latter so as to prevent the drawing of a partial vacuum following the pressure impulse in the pipe. The air vent may be provided in various forms.

In Figs. 1 and 2, the air vent comprises a valve passage 12 opening centrally through the base wall 10 into the inner end of the socket 9, and in the present instance defined by a small sleeve or tube 13 tightly fitted in a bore 14 formed in the wall. The tube 13 may be made of any suitable material, such for example as copper. Preferably, the tube 13 is slightly less in length than and is located centrally in the bore 14 so that the ends of the tube terminate slightly short of the external surfaces of the wall 10. The passage 12 is in communication with the inner end of a passage 15 extending axially into the handle 11 and opening through a cross passage 16 to the atmosphere at the periphery of the handle adjacent the shank 8.

A valve member 17, in the form of a flat circular disk, is adapted to move against the inner surface of the wall 10 across the lower ends of the bore 14 and the passage 12 to close the latter upon the building up of pressure in the cup body 6. Since the lower end of the tube 13 is spaced from the inner surface of the wall 10, the latter affords a yieldable seat for the valve member 17, thus insuring a tight seal during each pressure stroke. The yieldable seat presented by the wall 10 and the coacting area of the valve member 17 are air and water impervious, and when in contact prevent the out-filtration of air through the passage 12. These areas are not subject to deterioration, and afford a tight seal for the normal life of the cup 6. The valve member 17 is

suspended for free floating movement by a stem 18 which extends upwardly in peripherally spaced relation through the tube 13, and which is connected at its upper end to a perforated disk or 5 cross member 19 adapted to rest against the upper surface of the wall 10.

In use, the valve member 17 normally is suspended in open position under the force of its own weight. During the pressure stroke, the 10 pressure of the trapped air in the cup body 6 will force the valve member 17 tightly against the wall 10 to close the air vent. Upon subsequently lifting the handle 11 to expand the cup body 6, the valve member 17 will drop, thereby 15 opening the air vent and preventing the formation of a partial vacuum. Hence, in the repeated operation of the force cup, no suction is created in expanding the cup body 6, and the work performed during the pressure stroke is 20 not undone. The sludge or obstruction cannot be drawn backwardly out of the pipe, nor moved merely to and fro. On the contrary, the pressure impulses are cumulative in effect so that the pipe obstruction may be easily and quickly removed. 25

A modified form of air vent is shown in Figs. 4 and 5. In this form, a vent passage 20, non-circular and preferably square in cross-section, is formed in the wall 10, and opens therethrough 30 from the interior of the cup body 6 to the inner end of the socket 9. Formed in the lower end of the handle 11 directly over the passage 20 is a valve chamber 21. A passage 22 opens from the chamber 21 axially into the handle 11, and communicates through a cross passage 23 with the atmosphere. The inner end of the passage 22 is slightly enlarged, and a metal sleeve or tube 24 is snugly fitted therein. The inner end of the tube 24 defines a valve seat. Normally seated 40 against the wall over the passage 20 without fully closing the latter, and freely movable in the valve chamber 21 against the valve seat 24 to close the passage 22 upon the building up of pressure in the cup body 6 is a metal ball valve member 25. It will be evident that the ball 25 constitutes a check valve which will permit air to enter the cup body 6 when the latter is being expanded, and which will prevent air within the cup body from escaping. Both of the valve members 17 and 25 are mounted for free floating movement so as to insure quick closing and opening of the air vent passages at the start respectively of the pressure stroke and the suction stroke of the cup 6. By free floating movement 50 of the valve member is meant a movement, though restricted in extent, which occurs only in response to the weight of the member and to differences in air pressure, and which is not retarded by friction or other mechanical influences. 60

I claim as my invention:

1. A force cup comprising, in combination, a cup body of concave form and resilient material, said body having a peripheral sealing rim and a central external shank, said shank being formed with a socket separated from the interior of said body by a wall, said wall being formed with a bore opening therethrough from the interior of said body axially into said socket, a metal sleeve snugly fitted in said bore, said sleeve being less in length than said bore and being spaced from the inner face of said wall, a flat air impervious disk valve member suspended in said body for free floating movement against said face to close said bore, said member having a stem extending

outwardly through said sleeve, a cross member connected to said stem and adapted to engage the outer face of said wall to support said valve member, and a handle secured in said socket, said handle having an axial passage in communication at one end with said bore and opening at the other end to the atmosphere. 80

2. A force cup comprising, in combination, a cup body of concave form and resilient material, said body having a peripheral sealing rim and a central external shank, said shank being formed with a socket separated from the interior of said body by a wall, said wall being formed with a valve bore opening therethrough from the interior of said body into said socket, a metal sleeve snugly fitted in said bore, a valve member suspended in said body for free floating movement against the inner face of said wall to close said sleeve, said member having a stem extending outwardly through said sleeve, a cross member connected to said stem and adapted to engage said wall to support said valve member, and a handle secured in said socket, said handle having a passage in communication at one end with said bore and opening at the other end to the atmosphere. 90

3. A force cup comprising, in combination, a cup body of resilient material, said body having a central external shank, said shank being formed with a socket separated from the interior of said body by a wall, said wall being formed with a valve passage opening therethrough from the interior of said body into said socket, a free floating valve member movable against said wall to close said passage, said member having a stem extending through said passage, a cross member connected to said stem and adapted to engage said wall to support said valve member, and a handle secured in said socket, said handle having a passage in communication with said first mentioned passage and opening to the atmosphere. 100

4. A force cup comprising, in combination, a cup body of resilient material, said body having a central external shank, said shank being formed with a socket separated from the interior of said body by a wall, said wall being formed with a valve passage opening therethrough from the interior of said body into said socket, a substantially solid handle secured in said socket, said handle having a passage in communication with said first mentioned passage and opening at the periphery of said handle closely adjacent said shank directly to the atmosphere, and a free floating check valve coacting with said first mentioned passage to close the latter in response to pressure in said body. 110

5. A hand force cup comprising, in combination, a cup body of resilient material, said body having an external shank, a substantially solid handle secured at one end to said shank, an air vent passage formed in said shank and said handle and opening from the interior of said body to the atmosphere, said passage defining a valve seat, and a free floating weighted check valve member loosely confined in said passage in peripherally spaced relation therewith for permitting the entry of air into said body, and adapted to be closed against said seat in response to pressure within said body, said seat and said valve member having water and air impervious coacting surfaces for effecting a tight seal when 120 in engagement. 130

6. A force cup comprising, in combination, a cup body of concave form and resilient material, said body having a peripheral sealing rim and a central external shank, said shank being formed

with a screw threaded socket separated from the interior of said body by a wall, said wall being formed with a central passage non-circular in cross-section and opening therethrough from the 5 interior of said body centrally to said socket, a handle threaded into said socket, said handle being formed with a valve chamber in communication with said passage and with an axial passage in communication at one end with said chamber and opening at the other end to the atmosphere, a metal sleeve fitted into the inner end of 10 said last mentioned passage and constituting a valve seat, and a metal ball freely disposed in said chamber, said ball normally resting against said wall over said first mentioned passage and being adapted to move into engagement with said seat in response to pressure within said body.

15 7. A force cup comprising, in combination, a cup body of concave form and resilient material, said body having a peripheral sealing rim and a central external shank, said shank being formed with a socket separated from the interior of said body by a wall, said wall being formed with a central 20 passage non-circular in cross section and opening therethrough from the interior of said body centrally to said socket, an elongated handle secured in said socket, said handle being substantially solid throughout its length and being formed with a valve chamber in communication with said passage and with an axial passage in communication at one end with said chamber and opening 25 at the other end at the periphery of said handle to the atmosphere, the inner end of said last mentioned passage constituting a valve seat, and

a metal ball freely disposed in said chamber, said ball normally resting against said wall over said first mentioned passage and being adapted to move into engagement with said seat in response to pressure within said body.

8. A force cup comprising, in combination, a hollow cup body of resilient material, a handle secured to said body, said body being formed with a valve passage communicating with the atmosphere and defining at its inner end a resilient valve seat, a hard non-deformable sleeve fitted in said passage and serving to preserve the form thereof, and a free floating valve member having a metal face movable into engagement with said resilient seat in response to pressure in said body to seal said passage, said valve member having a stem extending loosely in peripherally spaced relation through said sleeve and having means for preventing withdrawal of said stem from said sleeve while permitting a limited extent of lost motion.

9. A force cup comprising, in combination, a cup body of resilient material, a shank on said body having a socket, a substantially solid cylindrical handle secured in said socket, an air vent 100 passage opening directly from the atmosphere through said handle and said shank to the interior of said body, a metal sleeve in said passage and at one end defining an annular metal valve seat, and a free floating valve member having a 105 metal face movable into and out of engagement with said seat respectively in response to the building up or lowering of the air pressure in said cup body.
